[57] CLAIM

The ornamental design for an access door for a computer printer, as shown and described.

DESCRIPTION

FIG. 1 is a front perspective view of an access door for a computer printer showing our new design and wherein the access door is shown in the attitude of its normal closed position;

FIG. 2 is a front perspective view of our design in its environmental setting but on a smaller scale than that of FIG. 1;

FIG. 3 is further front perspective view of our design but showing the access door in the attitude of its open position;

FIG. 4 is a front perspective view of our design similar to FIG. 2 but showing the access door in open position;

FIG. 5 is a front elevational view of our design;

FIG. 6 is an elevational view thereof as seen from the right end;

FIG. 7 is a transverse cross-sectional view taken substantially along line 7—7 of FIG. 5;

FIG. 8 is an elevational view thereof as seen from the right end;

FIG. 9 is a rear perspective view thereof showing the access door in the attitude of its open position;

FIG. 10 is a front perspective view of a second embodiment of our design and showing the access door in the attitude of its normal closed position;

FIG. 11 is another front perspective view of this second embodiment and showing the access door in an attitude corresponding to its open position;

FIG. 12 is a front elevational view of this second embodiment;

FIG. 13 is an elevational view thereof as seen from the left end;

FIG. 14 is a transverse sectional view taken substantially along line 14—14 of FIG. 12;

FIG. 15 is an elevation view thereof as seen from the right end; and

FIG. 16 is a rear perspective view thereof showing the access door in the attitude of its open position.

The portions shown in broken lines in the drawings are for illustrative environmental purposes only.
